IRRIGATING MEANS

Norris W. Young, Wilsonville, and Dorris S. Young, Newberg, Oreg.

Application May 13, 1941, Serial No. 393,280

7 Claims. (Cl. 299—19)

This invention relates to sprinkling systems, and, in particular, to sprinkling devices employed on the pipe lines of irrigating systems.

One of the difficulties common to most water sprinklers is the fact that they spread the water over a substantially circular area, and, as a result, when a number of such sprinklers are required to be used, the sprinkled areas must either considerably overlap and thus cause portions of the ground to receive an excess of water resulting in wastage, or else permit some of the intervening ground to remain unwatered.

Another objectionable feature found in some sprinklers is that they distribute the water unevenly in the area which they are designed to cover, delivering too much water in some portions and not sufficient water in other portions of the area.

The object of this invention is to provide an improved sprinkler head to be used for irrigating systems which will avoid such difficulties and avoid these objectionable features and which will be simple and practical in construction and which may easily be removed for cleaning or for other purposes.

The manner in which we obtain our object and other advantages will be hereinafter explained with reference to the accompanying drawings.

In the drawings:

Figure 1 is a side elevation of a sprinkler head embodying our invention and shown in place on an irrigation pipe (the irrigation pipe and connection being indicated in broken lines);

Figure 2 is a sectional side elevation of the same sprinkler head, drawn to a larger scale, and showing a pressure-equalizing valve within the sprinkler head;

Figure 3 is a similar side elevation, drawn to a smaller scale, but without the pressure-equalizing valve;

Figure 4 is a perspective elevation of one of the ring-shaped sections of which the sprinkler heads of Figures 1, 2 and 3 are formed;

Figure 5 is a sectional plan view of the sprinkler head, without the valve, the sprinkler head being drawn on the same scale as Figure 2 and the sections being taken at four elevations corresponding to the four ring-shaped sections of which the sprinkler heads of Figures 1, 2 and 3 are composed;

Figure 6 is an enlarged fragmentary vertical section of the peripheral wall of one of the ring-shaped sections, illustrating the manner in which the outer peripheral wall is deformed about a discharge opening;

Figure 7 is a fragmentary side elevation, on an enlarged scale, of the outside wall of the bottom ring-shaped section, taken on line 7—7 of Figure 2 and illustrating the shape of the discharge opening of this part of the sprinkler head;

Figure 8 is a fragmentary enlarged section of the peripheral wall taken on the line 8—8 of Figure 7; and

Figure 9 is a diagrammatic representation illustrating the manner in which each of the four ring-shaped sections of the sprinkler head of Figures 1, 2 and 3, provides for partial distribution of irrigating water in an approximately square plot of ground.

Referring first to Figures 2, 3, 4 and 5, the sprinkler head of our device is formed from a plurality (thus four in the sprinkler illustrated) of annular or ring-shaped sections or distributing members 10, 11, 12 and 13, which are preferably made to fit one into the other and which are secured together in axial alinement in any suitable manner at their outer peripheries, for example by welding or soldering. Their inner peripheries fit against a cylindrical wall or tube 22.

The shape and structural characteristics of these ring members 10, 11, 12 and 13 are best illustrated in Figures 2 and 4, the member shown in Figure 4 being member 11 or the next to the bottom one in the sprinkler of Figure 2. The outer perimeter of each of these members comprises a pair of cylindrical wall sections 14 and 15 connected by an arcuate annular wall section 16 which is substantially semi-circular in cross-sectional contour. Each member is formed with a flat annular bottom 17 terminating at its inner periphery in a downwardly-extending flange 18. The bottoms of members 11, 12 and 13 are provided with ports 19, the number of these ports 19 varying, as apparent from Figure 5, the reason for which will be explained later. There are no ports in the bottom of member 10. To enable the ring members to be nested into a press fit, when secured together, the outside diameter of wall section 15 is made equal to the inside diameter of wall section 14. The arcuate wall section 16 of each member is provided with ports through which the water is discharged in separate streams from the sprinkler head.

The bottom ring member 10 is secured to a locking ring 24 and the flange 18 of member 10 is turned over the inner periphery of the locking ring 24, while the bottom end of the inner tube 22 is turned over the bottom flange 18 as shown in Figure 2, these parts then all being firmly secured together.

The sprinkler head is coupled to a base 32 which is substantially semi-spherical in form and which terminates at the top in a cylindrical wall 33. At the bottom the base 32 is formed into a threaded boss 34 adapted to receive a standard pipe section. The cylindrical wall 33 is provided with cutouts 35 (see Figure 1) to accommodate and engage locking lugs 36 (Figure 2) projecting outwardly from a downwardly-extending flange 37 of the locking ring 24. The inside of the flange 37 is preferably beveled, as shown in Figure 2, and a ring gasket 38, of rubber or similar flexible material, is secured on the inside of the cylindrical wall 33 and forms a pressure seal with the flange 37 under the pressure of the water in the base of the sprinkler head. The top of the sprinkler head is formed by a cap 30 having a flange 31 which fits within the cylindrical wall 14 of the upper ring member 13 and is firmly secured therein in any suitable manner.

A very important feature of our invention resides in the arrangement and construction of the distributing ports in the ring members of the sprinkler head. In the case of the three upper ring members 11, 12 and 13 the ports A are cylindrical, with their axes inclined from the horizontal as shown in Figure 6. To figure adequate range in a stream of water delivered from such a port, we have found that it is essential that the metal immediately around the inside of the port be in a plane substantially perpendicular to the axis of the port, with the inside edge of the port sharply formed. In order to obtain this condition the metal surrounding each port is flattened in a small area as indicated at 21 in Figure 6.

The ports in the lowest ring member 10, which function to distribute the water over the ground surface immediately adjacent the sprinkler, we make rectangular in shape, as indicated at 20 in Figure 7. Furthermore, in order that these ports may produce fan-shaped streams of desired dimensions, they are formed, as indicated by Figure 8, by a tapered chisel-edged die which forces the metal inwardly, resulting in a somewhat imperfectly-formed edge 21 on the inside of the port which modifies the discharge stream passing therethrough. As is well known, a rectangular port, such as that illustrated will produce a fan-shaped stream in a plane at a right angle to the long axis of the port.

The bottom of the uppermost ring member 13 is formed with a large number of ports 19 (see Figure 5) connecting with the next ring member 12, and the tube 22 (Figure 2) has a plurality of large ports 27 connecting with ring member 12, with the result that the water pressure is substantially the same in ring members 13 and 12. The tube 22 has no ports connecting with ring members 11 and 10. The water in ring member 11 is all obtained from ring member 12, while water in ring member 10, is obtained from ring member 11. The bottom of ring member 12 is provided with only a reduced number of connecting ports 19, as indicated in Figure 5, but the bottom of ring member 11 has a large number of ports. As a result of this arrangement of bottom ports the water pressure in ring members 11 and 10 will be considerably less than in members 12 and 13.

Assuming that a predetermined desired pressure within the irrigation pipe line is constantly maintained, the method of operation of the sprinkler head may now be described with reference to Figures 5 and 9. Since, as mentioned at

the beginning of this specification, one of the objects of our invention is to have the sprinkler head disperse water over a substantially square area of land, such a square area is indicated by the outside broken border line in Figure 9, and this area is divided into quarter spaces 64, 66, 68 and 75. The sprinkler head in the center of Figure 9 is assumed to correspond exactly with that of Figure 5 and the distribution of sprinkler water from each ring member of the sprinkler head is shown for one-quarter area, respectively. Thus, in Figure 9, the quarter area 64 shows the distribution of water in that quarter from the corresponding section of ring member 10 only; quarter 66, from the corresponding portion of ring member 11 only; quarter 68, from the corresponding portion of ring member 12 only; and quarter 75, from the corresponding portion of top ring member 13.

20 The rectangularly-shaped ports 20 of bottom ring member 10 are all of similar size and equally-spaced, and their arrangement and size, in combination with the water pressure provided within ring member 10, are such that they produce sprinkling coverage indicated by the broken line areas 65 in quarter 64 of Figure 9.

In ring member 11 the distributing ports are round, are all of the same size, and are equally-spaced. The size of these ports is such that they 30 will produce a sprinkling coverage in each quarter corresponding to the broken line areas 67. It will be noted that the range of the streams from these ports cover an area just beyond that covered by the streams from the ports 20 of ring member 10, this being caused entirely by the difference in the size and shape of the ports of the two ring members since the pressure within these two ring members is substantially the same.

In ring member 12 the discharging ports are 40 three sizes. There are four groups of five ports each, indicated by the reference character 69 in Figure 5, which are all of the same size and which are spaced symmetrically around the perimeter of the ring member 12. These ports distribute water over spaces indicated by the broken line areas 70 in Figure 9. The ring member 12 also has four other groups of five ports each, these ports being shown at 73 and 71 in Figure 5. In this second series of groups the ports are 50 not all of the same size, but the middle ports 71 are smaller than the two ports 73 on either side. As a result, each of the four ports 71 covers an area indicated at 72 in Figure 9, while the neighboring ports 73 cover areas indicated at 55 74 which extend a longer distance from the sprinkler head. In the top ring member 13 there are four groups of three ports each. The center port 76 in each of these groups is larger than any of the others in either ring member 12 or ring member 13, and is adapted to cover the broken line area 77. The other two ports 78 in each of these groups are adapted to cover areas at slightly less range, these areas being indicated at 79 in Figure 9.

65 By imagining the four quarters of Figure 9 superimposed one above the other, the manner in which the entire surface in each quarter of an approximately square area of ground will be covered by the sprinkler head can be visualized.

70 In the description thus far it has been assumed that a constant pressure is maintained in the irrigation pipe line, and thus that constant predetermined pressures are present in the ring members of the sprinkler head, causing their ports to distribute the water over predetermined

areas. However, if in the irrigation system it is impossible to maintain a constant desired pressure throughout the entire length of the pipe line, a suitable pressure-equalizing valve may be inserted within the sprinkler head and used in conjunction with the sprinkler head. Such a valve member is shown in Fig. 2, which valve has inlet ports 44 in communication with the source of supply from pipe 34 and outlet ports (not shown), which communicate with the chamber within tube 22.

A removable screen 39, preferably conforming in general to the semi-spherical shape of the sprinkler base 32, is inserted in the sprinkler as shown in Figures 2 and 3, and a second removable screen 29, preferably cylindrical in shape, is inserted in the tubular member 22. To prevent any possible deforming of the screen 29 and also in order to retain the screen 29 in place when the pressure-equalizing valve is not used on the sprinkler head, the tube 22 is provided with a plurality of inwardly-deformed segments 28 (Figure 3) which are adapted to bear slightly against the outside surface of the cylindrical screen 29.

Although our sprinkler head has been illustrated and described as composed of four ring members, arranged in the manner specified, it would be possible to provide more or less than this number. In some instances we have found that three ring members can be made to suffice. For general use, however, we consider the construction of the sprinkler head as illustrated in the drawings to be the most serviceable and practical. It would also of course be possible to make other modifications in the construction of the sprinkler head without departing from the principle of our invention, and it is not our intention to limit our invention otherwise than as set forth in the attached claims.

We claim:

1. In a sprinkler of the character described, a plurality of similar ring-shaped sections, said sections arranged one above the other about a central chamber, means for delivering water under pressure into the bottom of said chamber, said chamber discharging directly into an upper ring section, ports connecting adjacent ring sections whereby water will pass downwardly through said sections successively, said ports and sections so arranged that the pressures in said sections will be decreased successively, each of said sections having a plurality of discharge outlets, said outlets being of various size depending upon the pressure to be maintained in the particular ring section and upon the particular area to be serviced by the stream from the outlet, and the whole so arranged that the streams from said outlets will not interfere with each other but will each cover a predetermined ground surface area.

2. In a sprinkler, a plurality of ring-shaped sections, said sections arranged one above the other, a central tube-shaped inner member, said ring sections fitting against the outside of said member, said member discharging into an upper ring section, ports connecting said upper ring section with a lower ring section permitting water to enter said lower section from said upper section but maintaining a higher pressure in said upper than in said lower section, each of said sections having a plurality of discharge outlets, said outlets in said upper ring section adapted to cause streams to be projected therefrom at an inclined angle, said outlets being of various size depending upon the pressure to be main-

tained in the particular ring section and upon the particular area to be serviced by the stream from the outlet, and the whole so arranged that the streams from said outlets will not interfere with each other but will each cover a predetermined ground surface area.

3. In a sprinkler, a plurality of ring-shaped sections, said sections arranged one above the other about a central chamber, each section having an outer peripheral wall which is arcuate in vertical cross-section, means for delivering water under pressure into the bottom of said central chamber, said chamber discharging directly into an upper ring section, ports connecting adjacent ring sections whereby water will pass downwardly through said sections successively, said ports so arranged that the pressures in said sections will be decreased successively, each of said sections having a plurality of discharge outlets in its outer peripheral wall, said outlets being of various size depending upon the pressure to be maintained in the particular ring section and upon the particular area to be serviced by the stream from the outlet, and the whole so arranged that the streams from said outlets will not interfere with each other but will each cover a predetermined ground surface area and the streams from said outlets will be of decreased length successively downwardly, a base for said sprinkler, said base adapted to be attached to a pipe line, means for coupling said sprinkler to said base.

4. The combination set forth in claim 3 with said peripheral walls of said sections being deformed about said discharge outlets to cause the inside surface of the wall portion surrounding each outlet to lie in a plane perpendicular to the axis of the outlet, whereby to enable the range of the streams from said outlets to be predetermined more definitely.

5. In a sprinkler of the character described, a plurality of separate sections arranged one above the other, a passageway extending upwardly through said sprinkler, said passageway terminating in the uppermost of said sections, means for delivering water under pressure to the bottom of said passageway and thereby into the uppermost of said sections and thence through restricted ports to the lower sections successively in such manner that the water pressure in one section will be greater than the pressure in a lower section, each of said sections having a plurality of discharge outlets, said outlets so positioned and made of such size, with respect to the pressures in said sections, that the streams from said outlets will not interfere with each other but the streams from the outlets of one section will be projected further than the streams from the outlets of a lower section and each stream will cover a predetermined ground surface area, the topmost outlets of said sprinkler made of such size as to throw the longest streams and to project water into the corner portions of an approximately square ground surface area, whereby said sprinkler will function to distribute water over a square area.

6. The combination set forth in claim 2 with the addition of a removable screen within said tube-shaped inner member.

7. The combination set forth in claim 3 with said sprinkler removably coupled to said base and with a removable screen located in said base.
